UNITED STATES PATENT OFFICE.

SAMUEL W. FRIES AND ERVIN E. MALOTT, OF KANSAS CITY, MISSOURI.

MOP HEAD.

Application filed March 29, 1926. Serial No. 93,213.

The present invention relates to mop constructions, with particular reference to mops of the combined mop head and wringer type, and aims to provide a novel form of connection between the mop head frame and the ferrule member which is attached to the mop stick.

Accordingly, we have devised a mop and wringer structure in which a sliding connection is provided between the mop head frame and the ferrule member, permitting a relative longitudinal sliding movement between the ferrule member and mop head in the manipulation of the latter for mop wringing purposes, while this connection is adapted to prevent any relative sliding movement between the ferrule and mop head during the usual operation of the mop for scrubbing purposes.

In embodying the proposed improvements in their preferred form, we provide a pin and slot connection between the ferrule member and the mop head, adapted to permit the necessary longitudinal sliding movement for positioning the mop head for the wringing operation, and form one end of the slot with a seat for maintaining the pin against any longitudinal movement during the actual scrubbing operation.

A further feature of the improved construction is the provision of the ferrule member proper with an extension past the point of mounting of the wringer device sufficient to constitute a ferrule socket adapted for receiving the mop stick, and permitting the renewal of said stick when necessary.

With these general objects in view, the invention will now be described by reference to the accompanying drawing illustrating one form of construction which we have devised for embodying the proposed improvement, and which shows particular features and combinations deemed to be novel will be specifically set forth and claimed.

In the drawing—

Figure 1 is a side elevation of a mop construction illustrating one form of embodiment of the proposed improvements, the mop stick being partly broken away;

Figure 2 is a plan view of the same;

Figure 3 is a vertical section on the line III—III of Figure 1;

Figure 4 is a similar sectional view, illustrating a section taken on the line IV—IV of Figure 2; and

Figure 5 is a side elevation similar to Fig-

ure 1, but illustrating the mop head swung into depending relation to the ferrule, for effecting the operation of the wringer.

Referring now to the drawing in detail, this illustrates the invention as comprising a skeleton mop head frame 10 which may be constructed of wire material to provide a loop 12 at its front end for the attachment in the usual manner of the mop cloth 14, the intermediate portion of the frame comprising side loops 15 which are connected by parallel strands 16 of the wire with suitable laterally extending loops 17 at the rear end of the mop head, as clearly shown in Figure 2. Upon the parallel intermediate strands 16 of the wire frame is mounted a bracket element 18 preferably formed of sheet metal crimped over the strands 16 for rigidly connecting the same, the sides of the bracket being then formed into parallel upstanding bracket portions 19 extending longitudinally of the mop head. In these upstanding portions 19 of the bracket element are formed parallel longitudinal slots 20 for slidably mounting a pin 22 which is carried by the parallel lugs 24 projecting laterally from the lower end of the ferrule member 25, as clearly shown in Figures 1, 3 and 5. This ferrule member is of the usual sheet metal construction, and intermediate its ends is provided with a tubular bearing element 26 for mounting the shank portion 27 of a wringer device, which terminates in a loop 28 for receiving the other end of the mop cloth 14 (see Figure 5). On the opposite side of the ferrule member the wringer device is formed with the usual type of handle or crank 30 and knob 31 for convenient operation of the wringer device in the wringing operation.

As clearly shown in Figures 1 and 5, the forward ends of the longitudinal slots 20 are turned slightly downward for the purpose of seating the pin 22 as indicated in Figure 1, and thereby preventing any longitudinal movement of the pin 22 when the mop is being used for scrubbing. This portion of the bracket element is practically midway between the ends of the mop head frame, so that the operating pressure is thus exerted practically centrally of the mop head in the actual scrubbing operation.

We also provide the ferrule member with an extension past the bearing sleeve 26, as indicated at 33 for providing a suitable ferrule socket into which to insert the usual mop stick member 34, the latter being secured in

position by the usual pins 35,—see particularly Figure 4. In this way the mounting and operation of the wringer device is not interfered with in any way, and the mop stick 34 5 may be renewed from time to time, without necessitating any discarding of the mop head and wringer, these parts of course lasting indefinitely.

It will thus be seen that we have devised 10 a practical and efficient construction for carrying out the desired objects of the invention. The mop head frame is cheaply constructed, and the pressure exerted through the handle and ferrule member is applied, 15 as above indicated, at the most efficient point of the mop head frame, and the bracket element provides an extremely simple form of attachment between the ferrule member and the mop head, with no unnecessary parts 20 or links, for allowing the required relative movement between the ferrule member and mop head in the change from scrubbing to wringing position. That is to say, the pin and slot form of connection allows the necessary longitudinal sliding movement, and the 25 downturned front ends of the slots provide for practically locking the parts against any relative longitudinal movement in the use 30 of the mop for scrubbing. When the handle is lifted, and the pin 22 thereby moved to the rear end of the slots 20, it is obvious 35 that the mop head will then swing downwardly into depending relation to the ferrule member, as illustrated in Figure 5, ready for operation of the wringer device. The laterally spaced arrangement of the loops 17 at the 40 rear end of the mop frame permits this end of the frame to clear the lower end of the ferrule member, and thus enables us to maintain as compact a construction of mop frame 45 as possible. The ferrule extension 33 is a valuable and useful feature, permitting renewal of the mop stick without effecting the wringer mounting, and enabling us to employ the same combined mop and wringer device 50 indefinitely, by simply renewing the mop stick within this ferrule extension.

While we have illustrated what we regard 55 as the preferred form of embodiment of our invention, we desire to reserve the right to make such changes or modifications as may fairly fall within the scope of the appended claims.

What we claim is:

55 1. A mop and wringer structure comprising a mop head frame having a bracket element, a ferrule member having a connection slidably engaging said bracket element

and permitting said frame to swing into depending relation to said ferrule at one of the 60 limits of said sliding movement, means preventing relative sliding movement of said ferrule and bracket elements at the other limit of said movement, a mop cloth attached to said frame, and a wringer device journaled 65 in said ferrule and also attached to said mop cloth and operative to wring the same when said frame is in depending position.

2. A mop and wringer structure comprising 70 a mop head frame having a rigid upwardly projecting bracket element, a ferrule member having a connection slidably engaging said bracket element and adapted to be seated against relative sliding movement at the forward end of said bracket element while 75 permitting said frame to swing freely into depending relation to said ferrule at the rear end of said bracket element, a mop cloth attached to said frame, and a wringer device journaled 80 in said ferrule and also attached to said mop cloth and operative to wring the same when said frame is in depending position.

3. A mop and wringer structure comprising 85 a mop head frame having a rigid upwardly projecting bracket element formed with a longitudinal slot, a ferrule member having a pin slidably engaging said slot, the forward end of said slot extending downwardly and preventing sliding movement of 90 said pin when seated in said forward end of said slot, said frame being adapted to swing downwardly into depending relation to said ferrule when said pin is at the rear end 95 of said slot, a mop cloth attached to said frame, and a wringer device journaled in said ferrule and also attached to said mop cloth and operative to wring the same when said frame is in depending position.

4. A mop and wringer structure comprising 100 a mop head frame having a bracket element, a ferrule member having a connection slidably engaging said bracket element and permitting said frame to swing into depending relation to said ferrule at one of the 105 limits of said sliding movement, and means preventing relative sliding movement of said ferrule and bracket elements at the other limit of said movement, the upper end of said frame, when the latter is in depending relation, being forked for clearing said ferrule member in swinging to said depending position.

In witness whereof we hereunto affix our signatures.

SAMUEL W. FRIES.
ERVIN E. MALOTT.
